GRAVER AND SCREW DRIVER SHARPENING FIXTURE

Irvin Waller, Chicago, Ill.

Application October 4, 1950, Serial No. 12,442

Term of patent 14 years

(Cl. D54—13)

To all whom it may concern:

Be it known that I, Irvin Waller, a citizen of the United States, residing at Chicago, county of Cook, and State of Illinois, have invented a new, original, and ornamental Design for a Graver and Screw Driver Sharpening Fixture, of which the following is a specification, reference being had to the accompanying drawing, forming a part thereof, in which:

Figure 1 is a perspective view of the instrument; Fig. 2, a plan view; Fig. 3, a side elevation view; Fig. 4, a front elevation view; Fig. 5, a side elevation view taken from the position opposite that of Fig. 3; and Fig. 6, a bottom view.

I claim:

The ornamental design for a graver and screw driver sharpening fixture, as shown.

IRVIN WALLER.
